United States Patent Office.

WILLIAM BALL, OF CHICOPEE, MASSACHUSETTS.

Letters Patent No. 76,381, dated April 7, 1868.

IMPROVEMENT IN STEAM-GENERATORS.

The Schedule referred to in these Letters Patent and making part of the same.

TO ALL WHOM IT MAY CONCERN:

Be it known that I, WILLIAM BALL, of Chicopee, in the county of Hampden, and Commonwealth of Massachusetts, have invented a new and useful Improvement in Steam-Boilers; and I do hereby declare that the following is a full, clear, and exact description thereof, reference being had to the accompanying drawings, making a part of this specification, and to the letters of reference marked thereon, in which—

Figure 1 is a side elevation of a steam-boiler.

Figure 2 is a longitudinal vertical section through fig. 1.

Figure 3 is a transverse vertical section through the line F G, fig. 1.

Figure 4 is an end elevation of said boiler.

Figure 5 is a sectional view, on a scale of one-eighth of full size, showing three water-tubes and the superincumbent fire-brick; and

Figure 6 is a plan view of said tubes and fire-brick on the same scale.

My invention relates to a certain construction of the upper part of the fire-box of a stationary horizontal-flue steam-boiler, and consists of a series of water-tubes, extending across the top of the fire-box, either longitudinally or laterally, and connecting the water-spaces at each end of the fire-box, or at each side of the same, and further, of a layer of fire-brick, so constructed as to rest securely upon such water-tubes, and form a top for the fire-box, in place of the crown-sheet and appurtenances generally used to cover the fire-box of boilers.

The construction of my invention is as follows: The body B of the stationary horizontal-flue steam-boiler, shown with its fire-box A and smoke-chamber C, is similar to an ordinary steam-boiler in all respects, except in the application of my invention to the upper part of the fire-box. The sides i i' of the water-space c', around the fire-box, are made to meet at the upper edges, and form a tight joint at h h, instead of being continued over the fire-box, in the form of a crown-sheet and outer shell. The water-tubes c c, formed of thick boiler-iron, are then inserted at equal distances apart, as shown in figs. 2 and 3, being placed below the proper water-line. One end of the tubes enters the inner plate i' of the water-lining, at the front end of the fire-box, and the other end enters the plate i, at the rear of such box, the joints being made water and steam-tight, in the usual manner of inserting and fastening flues in steam-boilers. The size of the tubes, relatively to the capacity of the boiler, which I have found efficient, will appear from an examination of figs. 2 and 3, the scale in those figures being three-eighths of one inch to the foot, but the same may be varied according to the use to which the boiler is to be put, and various other circumstances. In general, I propose to make the water-tubes of such a diameter, and to use such a number of tubes, as to afford as much or more heating-surface in the top of the fire-box as would be obtained by the use of a crown-sheet.

The tubes c c, instead of running lengthwise of the fire-box, as shown, may be arranged laterally or from side to side of the fire-box, being placed below the water-line of the boiler, in either case, and so that a free circulation of the water of the boiler through the tubes c c, and water-spaces c', will be allowed. Upon the water-tubes c c I place fire-brick b b, the length of each brick being equal to the distance between the axes of two adjacent tubes, and the breadth being suitable for such length. The lower edges of the ends of each brick are removed, and a concave depression or groove formed at the lower edges, as shown in fig. 5. The curve of the concave groove is such that the fire-brick comes in contact with the upper part only of the water-tube c, thus leaving nearly the entire surface of the latter exposed to the heat, while the under surface of the brick is about on a level with the centre of the water-tube. I have found it desirable to construct the fire-brick of such dimensions that their edges do not meet above the water-tubes, so that any slight irregularities in the edges will not prevent the brick from going to place readily. The interstices between the bricks are to be filled with fire-clay or other suitable material.

I am aware that other fire-resisting substances may be properly shaped and then used in place of the fire-brick described, but I prefer the fire-brick, as being easily moulded in the desired form, durable, and readily fitted in place. The space above the fire-brick is open to the air, so that the brick can be removed and renewed at any time, and it is evident that the whole operation of replacing the brick when needful is so simple and speedy that it can be performed by any unskilled person, and while steam is up in the boiler, if necessary.

By the use of the described arrangement of water-tubes and fire-brick, the construction of steam-boilers is

much simplified, inasmuch as the crown-sheet, with its numerous stays, is dispensed with, and its place supplied by a much more durable and simple device. In actual operation, the fire-brick acts with great efficacy to reflect the heat downward upon the fuel, causing it to ignite on top as well as at the bottom; and steam-boilers, the fire-boxes of which are provided with my said improvement, have shown increased capacity for generating steam. It will be evident, also, that the chances of explosion or collapse in case of low water are greatly lessened by dispensing with the crown-sheet.

Having thus described my invention, what I claim as new therein, and desire to secure by Letters Patent, is—

1. In a stationary horizontal-flue boiler, a fire-box, made open from bottom to top, and without a crown-sheet.
2. I claim the water-tubes *c c*, extending across the upper part of the fire-box, and entering the water-spaces at the sides or ends of the fire-box, as described, in combination with a covering of fire-brick, or other like material, the whole arranged and operating substantially as described, and constituting a substitute for the crown-sheet used over the fire-box of stationary steam-boilers.

WM. BALL.
